UNITED STATES PATENT OFFICE.

ASA E. REED, OF SAN BERNARDINO, CALIFORNIA.

POWER-GENERATOR.

1,369,542.

Specification of Letters Patent. Patented Feb. 22, 1921.

Application filed February 14, 1920. Serial No. 358,586.

To all whom it may concern:

Be it known that I, ASA E. REED, a citizen of the United States, residing at San Bernardino, in the county of San Bernardino, 5 and State of California, have invented new and useful Improvements in Power-Generators, of which the following is a specification.

This invention relates to an improvement 10 in power generators of that type designed to be operated by the air or water currents, or by the ocean waves, and in which the action of the force is directly expressed in the movement of the generator.

15 The essential object of the invention is to produce a generator of this type in which movement is generated in the same direction without regard to the direction of the force, so that a change of direction of the latter, 20 will not result in a reversal of the generator. This dispenses with complicated reversing mechanism as usually employed in devices of this type, and permits a more simple and economical construction.

25 The invention involves the construction of a power member adapted for rotation and provided with a plurality of series of fins mounted on individual pivots, and limited in movement to either side of the plane of 30 the member by stops. The projection of the fins beyond the plane of the member provides inclined sections against which the force is directed to impart movement to the member. The rests are adjustable, so that 35 the degree of inclination of the sections or fins may be controlled at will, to thereby vary the speed and power of the power member as may be desired.

The power member is substantially 40 rectangular, with each series of fins occupying a space of substantially one-fourth of the area of such rectangular form. Each set of fins is, however, arranged at right angles to the adjacent set or series, so that the diagonally-related sets of fins are in operation 45 at one and the same time. If however, reversal of force occurs, the opposing sets of fins are at once brought into play and movement of the power member continues in the 50 same direction as before.

The invention is illustrated in the preferred form and in the single application in the accompanying drawings, in which:—

55 Figure 1 is a view in side elevation of the improved power generator.

Fig. 2 is a horizontal section on the line 2—2 of Fig. 1.

Fig. 3 is a vertical section on the line 3—3 of Fig. 2.

Fig. 4 is an enlarged detail, illustrating 60 the mounting of the stops to permit their adjustability.

Fig. 5 is an enlarged detail illustrating the mounting of a fin.

The improved power generator is here 65 shown as including a single power member, comprising a rectangular outer frame 1, having a central hub 2, and division bars 3, radiating from the hub to the central points of the respective side of the frame. The 70 frame is thus divided into four equal sections, and as will be plain hereinafter, each section is to be provided with one series of fins.

The fins 4, which may be of any length 75 and width required of the particular frame section, are of metal, and may if desired be reinforced by longitudinal bars 5, as shown. The inner longitudinal edges 6 of the fins 80 are supported on or connected to pivot rods 7, which in turn are pivotally mounted at the respective ends in the outer frame and division bars of such frame.

The fins are here shown as arranged in series, that is a certain number of such fins 85 mounted for co-operative action under the force influence. Each certain number of fins so mounted constitute an independent series, and will be so termed hereinafter. The adjacent series of fins are mounted at 90 right angles to each other, that is the fins of one series will extend in one direction, while the fins of the adjacent series extend in directions at direct right angles. Therefore successively about the power member, 95 the series of fins will be in successive series, each following series being at right angles to the immediately preceding series.

The fins of each series are to be controlled and operated in an identical manner, and as 100 will be obvious will be angled on their pivot rods, with relation to the plane of the frame, so that the moving force acting against such angled fin, will impart movement to the member as a whole.

To limit the angled relation or pivotal swing of the fins, there is provided a series of rests for each end of all fins of a series, formed to limit movement of the fins in either direction. These rests or stops are 110

bars 8, adjustably secured to the outer frame bar part and to the division bar in which the particular series of fins are pivotally mounted. The bars are preferably formed 5 with longitudinal slots 9, to receive fastening means 10 from the frame bars, so that the stop bars may be moved to adjusted positions longitudinally of the frame bars. Projecting laterally in both directions from 10 the stop bars, are short sections 11, terminating in inturned stops 12, which latter are shaped to receive the end portions of the fins. It will be apparent that these stops 12 will effectively serve to limit the inclined 15 position of the fins in either direction, and that by adjustment of the stop bars, the degree of inclination of the fins may be varied as desired. It being apparent that the inclination controls the speed and therefore 20 the power of the device, the stops are thus adapted to govern the speed and power as may be found necessary.

The power member is preferably fixed by means of its hub to a long hollow bearing 25 member 13, and the latter rotatably mounted on a shaft 14. The ends of the shaft are supported in end frames 15, and the latter mounted on a suitable base 16.

In operation the current or wave motion 30 acts on the fins to incline those subject to such action, and by acting against the fins so inclined, will impart pressure to such fins. As the fins are mounted in a rotating body, such pressure is converted to a rotating 35 movement of the power member. The invention contemplates any desired mechanism whereby the rotation of the power member may be transmitted to any point for use, this detail being well understood mechanically, and forming no part of this invention.

From the construction described it will 40 be plain that the respective series of fins are successively brought into action and subjected to the force, and that all of the fins except the series in action, will be held by the force in substantially the plane of the member. However, if the force should reverse, it will be apparent that the movement 45 or direction of the power member will not be interrupted as the set of fins diagonally opposite the set acted on by the force when in one direction, will respond to the force in the opposite direction, with the effect, however, to continue the movement and direction of the power member.

Secured to all the fins regardless of series 50 are what may be termed banks, comprising outstanding metallic sections 17, which follow a curved line with the center of ro-

tation of the member as a center. These banks assist in creating a circular motion of the member by banking the force after the fin has reversed, that is has moved to its reversed position against the stops. 65

Of course the force moving in line with the axis of the power member will act on all the fins to incline them away from such force, and by the inclined face presented by the fins the force will rotate the member. 70 The reversal of the fins due to the reversal of the force will, as is obvious, simply act against an exactly similar plane, so far as the direction of force is concerned, and the direction of movement of the member will 75 be the same.

The device is to be used wherever power is to be generated from a flowing force, and when used as a current motor may be, and preferably is, completely submerged. Brace 80 members may be employed wherever necessary, and provision made for oiling the moving parts. The power members may be connected in series on the same shaft, and connected together, or used in tandem series, 85 or in any other arrangement that may be suggested by the conditions.

Having thus described my invention, what is claimed as new, is:—

1. A power generator, comprising a power 90 member mounted for rotation, and a plurality of fins mounted in said member, said fins being arranged in right-angularly related series in succession.

2. A power generator, comprising a power 95 member mounted for rotation, a series of individually mounted fins in the member, and arcuate U-shaped stops extending from each side of the member to limit the movement of the fins to a position at an angle to the plane 100 of the member and on each side thereof.

3. A power generator, comprising a rectangular power member mounted for rotation, a plurality of series of fins arranged in said member, the fins of one series being 105 at right angles to the fins of the next series, the fins of each series being pivotally supported at one edge to permit a swinging movement of the free edge to arrange such fin at an angle to the plane of the member. 110

4. A power generator, comprising a rotating member, a series of fins arranged therein and pivotally supported at one edge, adjustable means to limit the play of the free edges of the fins, and bars on the entire 115 series of fins arranged in a circular line about the center of rotation of the member.

In testimony whereof I affix my signature.

ASA E. REED.
